INVENTOR:
John Weigel,

Fig. 4.

BY John E. Jones.

ATTORNEY.

UNITED STATES PATENT OFFICE.

JOHN WEIGEL, OF CINCINNATI, OHIO.

GAS AND OIL BURNING HEATER.

Application filed June 22, 1921. Serial No. 479,646.

To all whom it may concern:

Be it known that I, JOHN WEIGEL, a citizen of the United States of America, and a resident of Cincinnati, in the county of

5 Hamilton and State of Ohio, have invented a certain new and useful Improvement in Gas and Oil Burning Heaters, of which the following is a specification.

This invention relates to heating-apparatus and, more especially, to hot-air furnaces adapted to the use of both gas and oil simultaneously, or either of them, as occasion may suggest or require in their operation, and thereby dispensing with the use 15 of coal, wood and similar lump and bulk fuels.

The prime object of the structure herein is to provide a multiple-burner device that is arranged in two sets, one at either side of 20 the axial-line of the furnace or heater, and intermediate two sets or series of upright air-receiving jacketed pipes in which the cool inlet-air is heated by the direct radiation of said several sets of multiple-burners 25 that are both adapted to use either gas or oil, or one to use gas and the other oil, and then said heated inlet-air thence conveyed by means of transverse passages or branch-pipes and longitudinal hot-air ducts with- 30 in, in the upper part of the main or body portion of the furnace-casing, into the hot-air conducting and distributing pipes that extend beyond, from the dome or crown of said casing into the rooms or apartments 35 above that are intended to be heated thereby.

The details of structure will be fully described in connection with the accompanying two sheets of drawings, in which—

Figure 1 is a perspective view of the device embodying my invention, but omitting the usual outside jacket or casing, and otherwise showing both the gas and oil burners as they appear in combined use;

Figure 2, a transverse rearwardly-extending sectional-perspective, taken on a line a little to the rear of the valved inlet or controlling feed ends of the burners, at the fore end of the furnace, and including the lower part of the main portion of the outer-casing, with the dome or crown of said outer-casing omitted;

Figure 3, a plan view of Figure 1, but including the upright walls or main body-portion of the outer-casing and omitting the dome; and—

Figure 4, a perspective view of the fur-

nace with the entire outer casing and dome intact and showing the complete device as it appears in use, with both sets of gas and oil burners installed therein.

60

The furnace shown in the drawings is one having a square or rectangular casing, with upright side-walls 5, 5, rear-wall 6, fore-wall 7 and a pyramidal or sloping dome or crown 8. Square openings or orifices 9 and 10 are provided side-by-side in the lower part of the front-wall 7 and fitted with vertically-slidable doors or closure-plates 11 and 12. The lower edges of the front, rear and side walls of the outer-casing terminate somewhat above the floor so as to provide large openings or orifices between the angle-iron leg-extensions 13 for the entrance of the cool air surrounding the lower part of the furnace to be passed through the furnace 75 for heating and thence into circulation in the apartments above for heating the same.

14, 14 indicate each one of a pair of horizontally-aligned longitudinal boxes or drums, shown square in cross-section, duly spaced 80 apart and arranged along the bottom of the furnace, and 15, 15 indicate each one of a similar pair of spaced and aligned boxes or drums arranged along the top of the furnace. The two sets or pairs of drums 14 and 85

15, at the opposite sides of the furnace, are vertically aligned and duly connected by means of upright pipes or tubes 16 that terminate top and bottom with the bottoms of the upper drums 15, 15 and the tops of the lower drums 14, 14, respectively, as best shown in Figure 2. Upright concentric pipes or tubes 17, 17, of lesser diameter than that of the pipes 16, are fitted within the latter and terminate top and bottom in the tops of the upper drums 15 and the bottoms of the lower drums 14, respectively, as also shown in said Figure 2, whereby the tubes form annular heating-jackets around the

90 said internal tubes 17, as well as passageways for the ready circulation of air from the lower set of drums 14, 14 to the upper set of drums 15, 15. Short horizontal branch-pipes 18 connect the lower drums 14, 14 with a lower longitudinal draft-pipe 19

100 at its fore end, such draft-pipe extending centrally between the said pair of lower drums 14, 14 and on a level with them, and a heat-collecting chamber or drum 20 is provided in the top of the furnace, with a 105

series of side-branches 21 leading to the pair of upper drums 15, 15, but having in-

95

100

105

110

verted-funnel shape or sloping side-walls 22 that form an expansion fire box or chamber for the heat units arising by radiation from the top-plates 23 of the two burner-boxes 24 and 25 that extend rearwardly from the front openings or orifices 9 and 10, respectively.

26 indicates a pair of suitably jetted or perforated gas-using twin-burners in the open-tunneled box or chamber 24, the full length of same ordinarily, and 27 indicates a pair of oil-using twin-burners in the adjoining open-tunneled parallel box or chamber 25, an additional oil-burner 28 being provided in said last-named box or chamber 25 for the larger-sized furnaces or those of greater capacity, as best shown in Fig. 1. A longitudinal trough or pan 29 is ordinarily provided in the said open-tunneled oil-chamber 25 for supporting the oil-burners and catching any drip therefrom in use, as well as permitting its ignition and consumption simultaneous with that of the burner-jets themselves, during such use, so as to avoid accumulations therein.

Both ends of the furnace-casing are provided with the openings 9 and 10, especially in the event the device is intended for more than the ordinary heating capacity, and then gas and oil burners of greater or lesser length can be inserted from both ends of the open-tunneled burner-boxes 24 and 25 to supply the desired initial heat.

Side-orifices 30 are provided in the fore end of the lower draft-pipe 19 for the exit of any fumes and noxious vapors from the lower branches 18, in passing onward and outward through the exit-orifice 31 at the rear or far end of the draft-pipe 19, for discharge thence into the chimney or flue.

The bottom of a narrow longitudinal throat or chamber 32 is open and provides for the rapid ascent of the air between the two burner-boxes 24 and 25, and thence 45 through the orifices 33 at the top of said internal throat or chamber 32 into and through a longitudinal series of vertical pipes or passages 34 that extend into the top of the upper central drum or chamber 50 20, whence such air passes onwardly in a heated condition into the dome 8 for distribution into the several conductor-pipes (not shown) for the apartments above. The air rising in chamber 32 also branches off 55 through openings 32^a made in the side walls thereof and passes outwardly through the expansion-chamber 32^b at both sides of the vertical pipes 34 and said chamber 32, and thence through the exits 38^a above.

60 Short vertical internal tubes or pipes 35 extend from bottom to top of the upper drums 15, 15, for passage and circulation of the heated air from below said upper drums 15, 15, in the hot fire-box or burner-chamber, 65 and thence passing onward into the apart-

ment-circulation of the said dome 8. The heat from the burners in the said fire-box or burner-chamber radiates directly from the burner-compartments 24 and 25 so as to directly attack the vertical tubes or encompassing-jackets 16 located in two series at both sides of said fire-box, and an extremely efficient means of heating said air arising from the floor surrounding the lower part of the encased furnace, or from an outside 75 source of supply, if desired, is produced.

The feed-tubes 36, 36, lead from any convenient source of supply to the twin-burners 26, 26, for gas, and an oil feed-tube 37 leads to the suitably valved oil-burners 27, 80 27 and 28, as best shown in Figure 1, convenient to the operator of the furnace.

It will be seen, at 38, in Figures 1 and 2, how the branch-tubes 21 are split and flanged and then coupled together by bolts 85 for the purpose of readily assembling and dismantling the furnace parts when put up for use, or taken down for repairs, cleaning, or packing, and for shipping, as occasion may require. These branch-tubes are preferably made up of split or two-part semi-circular telescoping sleeves and short thimbles or flanges 38^a, 38^a, the latter extending laterally from the upper air-drums 15, 15 and the middle drum 20, and, also, from 95 the lower drums 14 and the draft-tube 19.

It will readily be seen how the furnace, constructed as herein shown and described, can be used very economically and conveniently, with either gas or oil, as fuel, or both 100 at the same time if found expedient and advantageous, and to accord with the supply and cost of each, and, practically, a "two-in-one" fuel service of gas and oil, instead of coal or like bulky, loose and dirty fuel, inconvenient to handle, is the material and appreciable result.

Any shortage of gas may be readily remedied by using all oil in the furnace, or vice versa, and there would be no worry on the 110 part of the user on account of the shortage of either of said fuels, nor any smoke, dirt, ashes, poking, shoveling or the like occurring to inconvenience said user.

I claim:—

1. In a hot-air gas-and-oil-using furnace, the combination of a pair of spaced lower longitudinal air drums or chambers, a similar pair of spaced upper longitudinal air drums or chambers in vertical alinement 120 with said lower drums, an intermediate central lower draft-tube or exit-duct horizontally-aligned with said lower air-drums, horizontal branch-pipes connecting said lower air-drums with said central draft-tube or 125 exit-duct, upright inner air ducts or pipes leading from the bottoms of the said lower air-drums to the tops of the said upper air-drums, jackets or spaced tubes or pipes surrounding the said last-named inner air ducts 130

or pipes between the upper and lower air-drums, a centrally-disposed longitudinal upper air-chamber between the pair of upper air-drums and in horizontal-alinement therewith, horizontal branch-pipes connecting said central upper air-chamber with the said pair of upper air-drums, an inverted hopper or a central funnel-shape upper air-chamber, a twin pair of open-ended burner boxes arranged beneath the said central funnel-shape upper air-chamber and adapted to contain fuel burners, means for controlling said gas and oil burners, and heat-radiating plates or partitions forming the tops of and leading from the twin burner-boxes to the said centrally-disposed longitudinal upper air-chamber, substantially as herein shown and described.

2. In a hot-air gas-and-oil-using furnace, the combination of a pair of spaced lower longitudinal air drums or chambers, a similar pair of spaced upper longitudinal air drums or chambers in vertical alinement with said lower drums, an intermediate lower draft-tube or exit-duct horizontally-aligned with the said lower air-drums horizontal branch-pipes connecting said lower air-drums with said central draft-tube or exit-duct, upright inner air-ducts leading from the bottoms of the said lower air-drums to the tops of the said upper air-drums, concentric spaced tubes or pipes surrounding the said last-named inner air-ducts between the upper and lower air-drums, a centrally-disposed longitudinal upper air-chamber between the pair of upper air-drums, a central funnel-shape upper air-chamber, a pair of open-ended burner boxes arranged beneath the said central funnel-shape upper air-chamber and adapted to contain fuel-burners, means for controlling said gas and oil burners, a centrally-disposed series of draft flues or air tubes leading from a throat or chamber located between the burner-boxes to said central upper air-chamber, an auxiliary series of vertical tubes or air passages in the two main upper air-drums, and an outer-casing having a crown or dome and mounted on legs above the floor for the desired feed-supply of air from below to be heated and passed onward through the drums and pipes of the furnace into the dome or crown for distribution thence into and through the conductor-pipes into the apartments above, substantially as herein shown and described.

JOHN WEIGEL.
